UNITED STATES PATENT OFFICE.

CHARLES B. FOX, OF PROVIDENCE, RHODE ISLAND.

PROJECTILE.

1,091,922.

Specification of Letters Patent. Patented Mar. 31, 1914.

Application filed July 30, 1913. Serial No. 782,008.

To all whom it may concern:

Be it known that I, CHARLES B. Fox, a citizen of the United States, residing at Providence, county of Providence, and State of Rhode Island, have invented a new and useful Improvement in Projectiles, of which the following is a specification.

My invention relates to projectiles or shells, and has for its object to produce an article of this nature that will possess a wider range of execution and consequently cause a much greater destruction with the same amount of labor, material, and expense than the shells now in use. I accomplish this purpose by the construction presently described and shown in the accompanying drawings forming part hereof, and in which:

Figure 1 is a sectional side elevation of my improved shell ready for firing. Figs. 2, 3, 4 and 5 sectional views of the body of the shell separated. Fig. 6 a plan view of the shell. Fig. 7 a side elevation of the forward pin. Fig. 8 a plan view of the same. Fig. 9 a side elevation of the back pin. Fig. 10 a plan view of same. Fig. 11 a side view of the cap; and Fig. 12 a plan view of same.

Similar letters of reference designate corresponding parts throughout the several views.

My invention consists in making a shell of suitable material in two parts A and B each provided with a semi-circular recess C and a central channel C¹ leading into said recess and adapted to receive the pins hereafter described. The inner edges of these sections are so formed that they can be easily and securely joined, as by providing one section with a flange or terton C² and the other section with a mortise C³ adapted to receive said flange; and when said sections are thus assembled the chamber C⁴ is formed centrally thereof which contains the load of ammunition. Through each channel C¹ extends a pin D and a pin E, the forward pin D being provided with a head D¹ which, when the shell is loaded and ready for firing, sets slightly beyond the face of the body of the shell, as shown at D², which brings its tapered rear end D³ slightly in advance of the likewise

tapered point E² of the back pin E, as shown at E¹. Thus, my improved shell contains a central chamber into which the 55 tapering points of two pins project. The shell is then secured in a metal cap F at its rear, in the usual way, which is loaded for the purpose of hurling the projectile from the gun. When the head D¹ strikes an object, the pin D is driven back and, contacting with the point E² of the pin E, the shell is exploded. Because of the large capacity of this central chamber and the shell being sectional, the contents thereof 65 go in different directions and over a large area doing a damage considerably greater than that resulting from the explosion of the shells now in use which usually deliver their contents in a concentrated shape at 70 one particular place only.

Having now described my invention, what I claim as new and desire to secure by Letters Patent, is:—

1. A shell composed of sections each provided with a recess and a channel leading thereto, which sections, when assembled, form a central chamber; and pins extending through said channels and projecting into said chamber.

2. A shell provided with a central chamber and pins extending from each end of said shell and projecting into said chamber adapted to contact with each other.

3. A shell composed of two sections A 85 and B, each provided with a semi-circular recess C and channels C¹ leading to the same, and which sections, when assembled, form a central chamber C⁴, a pin D adapted to enter the channel in section A provided at its outer end with a head D¹ and having a tapered point D³ projecting into said chamber; a pin E adapted to enter the channel in section B provided with a tapered end E² projecting into said chambers, the said pins being so arranged that when the head D¹ strikes an object, the pin D will be forced against the pin E and cause the explosion; and a cap F, all substantially as shown and described.

CHARLES B. FOX.
